UNITED STATES PATENT OFFICE

2,604,216

FEEDER

Eugene Martin, Wesleyville, Pa., assignor to Read Standard Corporation, a corporation of Delaware

Application February 14, 1948, Serial No. 8,467

12 Claims. (Cl. 214—17)

1

This invention relates to material feeding means and particularly to a reciprocating piston type feeding mechanism for delivering material to a receiver from a source of supply, in which a pressure differential exists between the receiver and the source of supply. While the invention is susceptible to many applications, it is particularly adapted for feeding finely divided coal from a feed hopper at atmospheric pressure into a coal receiving tank in which the pressure may be in excess of 150 pounds per square inch.

It is an object of the invention to provide an improved feed mechanism of the character described wherein friction incident to reciprocation of the feed piston in the cylinder is minimized, while maintaining at all times an effectual seal against escape of pressure past the piston from the pressurized outlet to the non-pressurized inlet, and generally to provide a practical and efficient feeding apparatus.

Another object is to provide a construction and arrangement of parts, whereby the operation of devices of the above character is improved, with respect to obtaining high feeding capacity while maintaining the overall dimensions at a minimum.

Another object is to provide a feed mechanism of the character described in which material is delivered from a non-pressurized source of supply to a pressurized receiver on both the forward and return stroke of the feed piston.

Another object is to provide improved feed mechanism of the character described including novel means for completely discharging material from the feed piston into the pressurized receiver, the operation of the said discharging means being synchronized with the operation of the piston to function when the material carrying cavities of the piston communicate with the pressurized outlet.

Additional objects, advantages and features of the invention reside in the construction, arrangement and combination of parts, as will be understood from the preferred and practical embodiment of the invention hereinafter described and illustrated in the accompanying drawings, in which

Figure 1 is a view in side elevation of the novel feed mechanism with the feed hopper and receiving tank to which it is applied also shown in elevation and partly broken away;

Figure 2 is a longitudinal vertical central section through the novel feed mechanism;

Figure 3 is a sectional view taken on the line 3—3 of Figure 2;

Figure 4 is a sectional view taken on the line 4—4 of Figure 2;

Figure 5 is a plan view of the novel feed mechanism with a portion broken away and shown in horizontal central section;

Figure 6 is a sectional view taken on the line 6—6 of Figure 5; and

Figure 7 is a sectional view taken on the line 7—7 of Figure 5.

10 While the feed mechanism constituting my invention may be employed for feeding of various kinds of granular or finely divided solid material from a source of supply to a point of discharge, it is particularly adapted for delivery 15 of finely divided coal into a pressurized receiver, and it will be so described hereinafter.

The feeding device 10 comprises a cylinder 11, preferably formed for reasons later explained, by end to end related cylindrical housing sections 20, 12, 13 and 14, as best shown in Figure 1. The intermediate housing section 13 is provided between its ends with a downwardly opening discharge spout 15 connected with a pressurized tank or receptacle 16 into which coal drops by gravity 25 from the feeding device 10.

The other housing sections 12 and 14 are provided, respectively, at their ends adjacent the intermediate or discharge housing section 13 with upwardly opening intake spouts 17 and 18 arranged to receive coal by gravity from the hopper 19. The intake and discharge spouts are thus offset or spaced a distance apart longitudinally of the feeding device, with the discharge spout 15 being between and equidistant from the intake spouts 17 and 18.

The housing sections 12, 13 and 14 are rigidly secured together in any suitable manner, as for example, by bolts 20 passing through the abutting flanges 21 and 22 of the housing sections 12 and 13, and bolts 23 passing through abutting flanges 24 and 25 of the housing sections 13 and 14. As best shown in Figures 2 and 5, the end of the housing section 12 opposite the flange 21 is open and communicates in end to end relation with the crank case 26. Suitable means, as bolts 27, rigidly secure the crank case 26 to the flange 28 of the housing section 12. The opposite end of the crank case 26 is provided with a crank case cover 29 suitably secured, as by bolts 30, to the crank case 26.

A hollow piston 31 is mounted, as hereinafter described, to reciprocate in the cylinder 11 and is provided with the longitudinally spaced pockets 32 and 33 extending vertically therethrough. 55 These pockets are arranged so that in one ex-

treme position of the piston 31, the pocket 32 registers with intake spout 17 while the pocket 33 registers with discharge spout 15 as shown in Figure 2, and in the other extreme position of the piston 31, the pocket 33 registers with intake spout 18 while the pocket 32 registers with discharge spout 15.

The pockets 32 and 33 are identical in form and in describing the pocket 32 it will be understood that this applies also to the pocket 33. The pocket 32 is defined by the opposed transversely extending upright walls 34 and 35 and the opposed longitudinally extending upright walls 36 and 37, which, as best shown in Figures 2 and 6 diverge slightly from their upper to their lower ends, thus facilitating discharge of coal from the pocket when in registering position with the discharge spout 15. The pocket defined by the walls 34, 35, 36 and 37, is rectangular in horizontal section, as clearly shown in Figure 5, with the longitudinally extending walls 36 and 37 being preferably spaced farther apart than the transversely extending walls 34 and 35.

The piston 31 is provided with the cylindrical sleeve extensions 38 and 39, so that when the pocket 33 is moved to registering position with the discharge spout 15, as best shown in Figure 2, the sleeve 39 will close off the bottom of the intake spout 18 preventing the coal from dropping into the cylinder 11 behind the piston 31. The sleeve 38 performs a similar function when the cavity 32 is moved from the position shown in Figure 2 to registering position with the discharge spout 15.

As clearly shown in Figure 2, a slight clearance is provided between the periphery of the piston 31 including its sleeve extensions 38 and 39, and the innermost surfaces of the cylinder 11, thereby minimizing scoring, abrasion and freezing of the piston 31 in the cylinder 11 by the coal dust and particles that find their way between the piston and cylinder during operation.

The piston 31 is provided at its opposite ends with the longitudinally extending piston rods 40 and 41. The rod 40 is slidably mounted in a bearing 42 carried by a sleeve 43 which is preferably integrally formed with the upright wall 44 of the crank case 26. Similarly, the rod 41 is slidably mounted in a bearing 45 carried by a sleeve 46 which is preferably integrally formed with the end wall 47 of the cylindrical housing section 14.

Piston 31 is operated from a crankshaft 48 extending transversely of the feed device 10 and journaled in the bearings 49 and 50, respectively, of the crank case 26, as best shown in Figure 3. The bearings 49 and 50 are mounted, respectively, in the removable bearing covers 51 and 52, which are secured in any suitable manner in the side walls of the crank case 26.

A pair of connecting rods 53 and 54, one at each side of the piston rod 40, operatively connect the crank 55 of the crank shaft 48 with the piston 31. The connecting rods 53 and 54 are rotatably mounted at one of their respective ends on the crank 55 and are oscillatably mounted at their respective opposite ends on the respective opposite ends of a transversely extending wrist pin 56 carried by the piston 31. The crank 55 is formed with a throw equal to one-half the horizontal distance between the center line of either intake spouts 17 or 18 and the center line of the discharge spout 15, so that upon reciprocation of the piston 31, the pockets 32 and 33 of the piston 31 will alternately register with the

intake spouts 17 and 18, and the discharge spout 15.

Since, as previously stated, clearance is provided between the piston 31 and cylinder 11, a pressure seal is provided between the non-pressurized intake spouts 17 and 18, and the pressurized discharge spout 15, in order to prevent escape of air from the pressurized discharge spout 15 through the said clearance and the blow back of coal therethrough.

The pressure seal is formed by a plurality of nonmetallic packing rings 57 surrounding the piston 31 and arranged to be received in an annular recess 58 of the inner wall of the housing section 13 of cylinder 11, the recess 58 being disposed between the intake spout 17 and discharge spout 15. Similar packing rings 59 are received in an annular recess 60 of the inner wall of the housing section 13 of cylinder 11, the recess 60 being disposed between the intake spout 18 and discharge spout 15. Spacer members 61 and 62 may be employed to suitably space the packing rings 57 and 59. It is also desirable to provide packing rings 63 and 64 between the cylinder 11 and piston 31 adjacent the sides of the intake spouts 17 and 18, respectively, opposite the packing rings 57 and 59, in order to minimize the leakage of fine particles of coal into the gear casing 26 and the housing section 14.

It is apparent from the above description that the outer surface of the piston 31 is entirely out of bearing contact with the cylinder 11, thereby minimizing abrasion and scoring of the piston and preventing seizing or binding of the piston in the cylinder by reason of coal particles that find their way between the cylinder and piston. The construction described, also provides an effective seal between the non-pressurized coal intake spouts and the pressurized coal discharge spout, permitting feeding of coal into the tank 16 in which the pressure may be for example, 150 pounds per square inch, from the bin 19 which may be at atmospheric pressure, with a minimum of escape of pressure and blow back of coal. The differential in pressure between the intake and discharge spouts may be greater or less than 150 pounds, the above example being cited for purpose of illustration only.

The upper and lower ends of the pocket 32 are provided, respectively, with the longitudinally extending spaced ribs 65 and 66 joining the walls 34 and 35 that define the cavity 32. The outer ends of the ribs 65 and 66 are flush with the circumference of the piston 31 and serve to prevent the upper and lower edges of the walls 34 and 35 from catching against the packing rings 57 as the piston 31 reciprocates. The pocket 33 is provided with similar ribs performing a similar function, and are therefore not described further. As best shown in Figure 6, the walls 36 and 37 of the pocket 32 form with the cylindrical wall of the hollow piston 31, longitudinally extending passages 90 and 91 which together with the similar passages at each side of the pocket 33 provide communication through the hollow piston 31 between the opposite ends of the cylinder 11 thereby permitting equalization of pressure during reciprocation of the piston 31.

In operation, with the piston 31 in the position shown in Figure 2, coal drops by gravity through the intake spout 17 into the coal receiving pocket 32. The piston 31 is then moved to the right through the crank shaft 48 and connecting rods 53 and 54 from a suitable source of power (not shown), to a position in which

the pocket 32 registers with the pressurized discharge spout 15. Coal drops by gravity from the cavity 32 through the discharge spout 15 and into the pressurized container 16. At the same time, the cavity 33 has moved into register with the intake spout 18 and receives coal from the hopper 19 while the coal in cavity 32 is being discharged. On the return stroke of the piston 31, the cavities 32 and 33 will reassume the positions shown in Figure 2, whereupon the coal in cavity 33 drops through discharge spout 15 and the cavity 32 receives another charge of coal from the intake spout 17.

In order to facilitate discharge of coal from the cavities 32 and 33, the means, now described, is provided. The upper wall portion of the housing section 13 opposite the discharge spout 15 has a boss 67 formed therewith which is provided with a transversely extending bore 68. A short pipe section 69 is threaded in one end of the bore 68 and is arranged to communicate with a pipe 70 through a valve 71. The pipe 70 leads from a suitable source of air under pressure which is admitted to the bore 68 by the valve 71 when either of the cavities 32 and 33 registers with the discharge spout 15.

The valve 71, which is normally closed, is moved to its open position upon contact of the shoulders 72 and 73 of a segment shaped cam 74 with the valve stem 75. The cam 74 is pivotally mounted on a bracket 76 which also forms a support for the valve 71, as best shown in Figure 4. Any suitable means may be provided for securing the bracket 76 to one side of the housing section 13.

The cam 74 is oscillated by means operatively connected to the crank shaft 48 for alternately bringing the cam shoulders 72 and 73 in engagement with the valve stem 75. This means includes a crank pin 77 secured eccentrically on the end of the crank shaft 48, which is connected by the pitman 78 with a stud 79 fixed to the cam 74 between its pivot and its periphery. Through the described connections, rotation of the crank shaft 48 effects oscillation of the cam 74.

With both the cam 74 and the piston 31 operated from the crank shaft 48, their movements are synchronized so that when the cavity 33 is in discharging relation with the discharge spout 15, as shown in the drawings, the cam 74 is in a position so that cam shoulder 75 opens the valve 71, whereby air under pressure enters the bore 68. A plurality of orifices 80 provide communication between the bore 68 and the inside of the housing section 13, through which orifices jets of air under pressure are directed into the upper end of cavity 33, facilitating discharge of coal from the cavity 33. Preferably, the pressure of the air jets is greater than the pressure in the receiving tank 16.

Now, when the piston 31 moves to the right, the cam 74 swings in a clockwise direction about its pivot, so that as the cavity 33 of piston 31 moves out of register with discharge spout 15, the shoulder 73 of cam 74 becomes disengaged from valve stem 75, permitting valve 71 to close and interrupting passage of air under pressure to bore 68 and orifices 80. As the piston 31 moves to the end of its stroke, the cavity 32 registers with the discharge spout 15 and the cam shoulder 72 engages the valve stem 75, again opening valve 71 and admitting air under pressure to the bore 68 and orifices 80.

While the cam and valve arrangement has been described above with reference to ad-

mitting air under pressure to a pair of coal receiving piston cavities, when said cavities alternately communicate with the pressurized discharge spout, it is apparent that the same arrangement may be used where a single cavity in the piston alternately communicates with a coal intake opening and a discharge spout, by providing merely one cam shoulder in place of the two cam shoulders 72 and 73 as shown in Figure 1.

Upon the coal being discharged from the cavities 32 and 33, a pressure is built up in the cavities since they are in communication with the pressurized tank 16. In order to prevent release of this pressure into the hopper 19 through the coal intake spouts 17 and 18, which would otherwise interfere with the free flow of coal into the cavities 32 and 33, vents 81 and 82 are provided in the upper wall of the housing section 13 between the discharge spout 15 and the intake spouts 17 and 18, as best shown in Figure 2. The vents 81 and 82 preferably communicate with the passages 83 and 84, respectively, which are formed in the housing section 13 and open to atmosphere. If desired the passages 83 and 84 may be connected to a source of suction to facilitate release of pressure from the cavities 32 and 33.

My prior application Serial No. 752,849, filed June 5, 1947, relates to the same general subject matter, and the disclosure in that application is intended to be incorporated herein by this reference in the interest of brevity. The generic claims will be made in the present application.

I claim:

1. Feed mechanism for delivering material from a non-pressurized zone into a pressurized zone, comprising a cylinder having offset intake and discharge openings communicating respectively with said non-pressurized and pressurized zones, a reciprocating piston in said cylinder, said piston being provided with a pocket communicating in one position of the piston in receiving relation with said intake opening and in another position of the piston in discharging relation with said discharge opening, said piston having a passage extending lengthwise therethrough for equalizing the pressure in the opposite ends of said cylinder as said piston reciprocates, and means within said cylinder between said openings and embracing said piston to form a seal between said cylinder and piston against escape of pressure from said pressurized zone to said non-pressurized zone.

2. Feed mechanism for delivering material from a non-pressurized zone into a pressurized zone, comprising a cylinder having offset intake and discharge openings communicating respectively with said non-pressurized and pressurized zones, a reciprocating piston in said cylinder, said piston being provided with a pocket communicating in one position of the piston in receiving relation with said intake opening and in another position of the piston in discharging relation with said discharge opening, venting means for releasing pressure trapped in said pocket prior to recommunication of said pocket with said intake opening, said piston having a passage extending lengthwise therethrough for equalizing the pressure in the opposite ends of said cylinder as said piston reciprocates, and means within said cylinder between said openings and embracing said piston to form a seal between said cylinder and piston against escape of pressure

from said pressurized zone to said non-pressurized zone.

3. Feed mechanism for delivering material from a non-pressurized zone into a pressurized zone, comprising a cylinder having offset intake and discharge openings communicating respectively with said non-pressurized and pressurized zones, a reciprocating piston in said cylinder, bearing means carried by said cylinder for slidably supporting said piston out of surface contact with the inside wall of said cylinder, said piston being provided with a pocket communicating in one position of the piston in receiving relation with said intake opening and in another position of the piston in discharging relation with said discharge opening, and means within said cylinder on each side of said discharge opening embracing said piston to form a seal between said cylinder and piston against escape of pressure from said pressurized zone.

4. Feed mechanism for delivering material from a non-pressurized zone into a pressurized zone, comprising a cylinder having offset intake and discharge openings communicating respectively with said non-pressurized and pressurized zones, a reciprocating piston in said cylinder, said piston being provided with a pocket communicating in one position of the piston in receiving relation with said intake opening and in another position of the piston in discharging relation with said discharge opening, a plurality of spaced members within said cylinder between said openings and embracing said piston to form a seal between said cylinder and piston against escape of pressure from said pressurized zone to said non-pressurized zone, said piston having a passage extending lengthwise therethrough for equalizing the pressure in the opposite ends of said cylinder as said piston reciprocates, and said cylinder being provided between said plurality of spaced sealing members with a vent arranged for communication with said pocket on the retracting stroke of said piston for releasing pressure, trapped in said pocket, prior to recommunication of said pocket with said intake opening.

5. Feed mechanism for delivering material from a non-pressurized zone into a pressurized zone, comprising a cylinder having offset intake and discharge openings communicating respectively with said non-pressurized and pressurized zones, a reciprocating piston in said cylinder, bearing means carried by said cylinder for slidably supporting said piston in peripheral spaced relation with respect to and out of surface contact with the inside wall of said cylinder, said piston being provided with a pocket communicating in one position of the piston in receiving relation with said intake opening and in another position of the piston in discharging relation with said discharge opening, a plurality of spaced members within said cylinder between said openings and embracing said piston to form a seal between said cylinder and piston against escape of pressure from said pressurized zone to said non-pressurized zone, and said cylinder being provided between said plurality of spaced sealing members, with a vent arranged for communication with said pocket on the retracting stroke of said piston for releasing pressure, trapped in said pocket, prior to recommunication of said pocket with said intake opening.

6. Feed mechanism for delivering material from a non-pressurized zone into a pressurized zone, comprising a cylinder having a pair of

spaced intake openings adapted for communication with said non-pressurized zone and a discharge opening intermediate said intake openings adapted for communication with said pressurized zone, a reciprocating piston in said cylinder, said piston being provided with a pair of pockets so spaced that they communicate respectively with one of said intake openings and said discharge opening in one position of said piston and with the other of said intake openings and said discharge opening in another position of said piston, said piston having a passage extending lengthwise therethrough for equalizing the pressure in the opposite ends of said cylinder as said piston reciprocates, and means within said cylinder between said discharge opening and each of said intake openings embracing said piston to form a seal between said cylinder and piston against escape of pressure from said pressurized zone to said non-pressurized zone.

7. Feed mechanism for delivering material from a non-pressurized zone into a pressurized zone, comprising a cylinder having a pair of spaced intake openings adapted for communication with said non-pressurized zone and a discharge opening intermediate said intake openings adapted for communication with said pressurized zone, a reciprocating piston in said cylinder, bearing means carried by said cylinder for slidably supporting said piston in peripheral spaced relation with respect to and out of surface contact with the inside wall of said cylinder, said piston being provided with a pair of pockets so spaced that they communicate respectively with one of said intake openings and said discharge opening in one position of said piston and with the other of said intake openings and said discharge opening in another position of said piston, and means within said cylinder between said discharge opening and each of said intake openings embracing said piston to form a seal between said cylinder and piston against escape of pressure from said pressurized zone to said non-pressurized zone.

8. Feed mechanism for delivering material from a non-pressurized zone into a pressurized zone, comprising a cylinder having a pair of spaced intake openings adapted for communication with said non-pressurized zone and a discharge opening intermediate said intake openings adapted for communication with said pressurized zone, a reciprocating piston in said cylinder, said piston being provided with a pair of pockets so spaced that they communicate respectively with one of said intake openings and said discharge opening in one position of said piston and with the other of said intake openings and said discharge opening in another position of said piston, bearing means carried by each end of said cylinder for slidably supporting said piston in peripheral spaced relation with respect to and out of frictional contact with the inside wall of said cylinder, venting means for releasing pressure trapped in said pockets prior to recommunication of said pockets with said intake openings, and means within said cylinder between said discharge opening and each of said intake openings embracing said piston to form a seal between said cylinder and piston against escape of pressure from said pressurized zone to said non-pressurized zone.

9. Feed mechanism for delivering material from a non-pressurized zone into a pressurized zone, comprising a cylinder having offset intake and discharge openings communicating respec-

tively with said non-pressurized and pressurized zone, a piston in said cylinder, means for reciprocating said piston, said piston being provided with a pocket adapted for alternate communication with said intake and discharge openings, means within said cylinder between said openings and embracing said piston to form a seal between said cylinder and piston against escape of pressure from said pressurized zone to said non-pressurized zone, a passage adapted to receive pressure fluid from a source of supply and deliver it into said cylinder diametrically opposite said discharge opening, a valve interposed in said passage, and actuating means coordinated with said piston operating means for opening said valve only when said piston pocket is in communication with said discharge opening.

10. Feed mechanism for delivering material from a non-pressurized zone into a pressurized zone, comprising a cylinder having offset intake and discharge openings communicating respectively with said non-pressurized and pressurized zones, a reciprocating piston in said cylinder, said piston being provided with a pocket adapted for alternate communication with said intake and discharge openings, means within said cylinder between said openings and embracing said piston to form a seal between said cylinder and piston against escape of pressure from said pressurized zone to said non-pressurized zone, a passage adapted to receive pressure fluid from a source of supply and deliver it into said cylinder diametrically opposite said discharge opening, a valve interposed in said passage, a pivotally mounted cam for opening and closing said valve, and means for operating said piston and cam in timed relation, said cam being formed to open said valve only when said piston pocket is in communication with said discharge opening.

11. Feed mechanism for delivering material from a non-pressurized zone into a pressurized zone, comprising a cylinder having a pair of spaced intake openings adapted for communication with said non-pressurized zone and a discharge opening intermediate said intake openings adapted for communication with said pressurized zone, a piston in said cylinder, means for reciprocating said piston, said piston being provided with a pair of pockets so spaced that they communicate respectively with one of said intake openings and said discharge opening in one position of said piston and with the other of said intake openings and said discharge opening in another position of said piston, means within said cylinder

between said discharge opening and each of said intake openings embracing said piston to form a seal between said cylinder and piston against escape of pressure from said pressurized zone to said non-pressurized zone, a passage adapted to receive pressure fluid from a source of supply and deliver it into said cylinder diametrically opposite said discharge opening, a valve interposed in said passage, and actuating means coordinated with said piston operating means for opening said valve only when said piston pockets are in communication with said discharge opening.

12. Feed mechanism for delivering material from a non-pressurized zone into a pressurized zone, comprising a cylinder having a pair of spaced intake openings adapted for communication with said non-pressurized zone and a discharge opening intermediate said intake openings adapted for communication with said pressurized zone, a reciprocating piston in said cylinder, said piston being provided with a pair of pockets so spaced that they communicate respectively with one of said intake openings and said discharge opening in one position of said piston and with the other of said intake openings and said discharge opening in another position of said piston, means within said cylinder between said discharge opening and each of said intake openings embracing said piston to form a seal between said cylinder and piston against escape of pressure from said pressurized zone to said non-pressurized zone, a passage adapted to receive pressure fluid from a source of supply and deliver it into said cylinder diametrically opposite said discharge opening, a valve interposed in said passage, a pivotally mounted cam for opening and closing said valve, and means for operating said piston and cam in timed relation, said cam being formed to open said valve only when said piston pockets are in communication with said discharge opening.
